CHARLES W. PECK, OF WATERBURY, CONNECTICUT, ASSIGNOR TO THE MATTATUCK MANUFACTURING COMPANY, OF WATERBURY, CONNECTICUT, A CORPORATION OF CONNECTICUT.

STRANDING-MACHINE.

1,271,518.

Specification of Letters Patent.

Patented July 2, 1918.

Application filed January 6, 1915. Serial No. 787.

To all whom it may concern:

Be it known that I, CHARLES W. PECK, a citizen of the United States of America, and residing at Waterbury, in the county 5 of New Haven and State of Connecticut, have invented new and useful Improvements in Stranding-Machines, of which the following is a specification.

My invention relates particularly to machines of the class of the Bigelow Patents 10 Nos. 1,043,896, 1,043,897 and 1,043,898 for uniting hooked links and perforated plates.

The main object of the present invention 15 is to provide a construction in which the plates may be automatically supplied from a hopper and connected up with the links to form a continuous strand or chain.

Other objects are to improve the details 20 of the mechanism to facilitate the operation and adjustment.

In the preferred form, as illustrated, a quantity of perforated plates is placed in a rotating hopper which keeps a vertical 25 guide supplied with the plates in an orderly arrangement. Hooked links are supplied on a guide adjacent the plate guide. The links are intermittently fed from the bottom of the link guide and the rear hook engages in one of the apertures in the plate in the 30 bottom of the plate guide. The strand is intermittently drawn through a horizontal strand guide extending at right angles from the base of the plate guide. At the next 35 operation, the front hook of the next link engages in the rear aperture of the first mentioned plate at the same time that the rear hook engages in the aperture of the succeeding plate.

The bottom plate is yieldingly supported 40 so that as the strand is pulled or drawn along, the plate is allowed to turn diagonally and follow the preceding plate along the horizontal strand guide.

The strand guide, draw-out mechanism 45 and tension mechanism may be constructed generally as indicated in the Bigelow Patents No. 1,043,896 or No. 1,043,898.

Figure 1 is a plan view showing the general construction and arrangement of a machine embodying the improvements of my 50 invention.

Fig. 2 is an enlarged detailed view show-

ing the link feeding and hook bending details.

Fig. 3 is a sectional view of the yielding support for the lowest perforated plate. 55

Fig. 4 is a side view in partial section showing the plate supply and strand guide and draw-out mechanism.

Fig. 5 is an enlarged side view showing the parts at the point of assemblage of the plates and hooks. 60

Fig. 6 is a vertical projection and transverse sectional view showing the plate and link supply guides, the link feed and bending tools. 65

Fig. 7 is a detached sectional view showing the plate supply hopper.

Fig. 8 is a sectional view showing the cam and slide for operating the part of the hook closing tools. 70

The apertured or perforated plates 10 are usually square and provided with holes in each corner. These are supplied in a vertical grooved guide 11. This guide is kept 75 filled from a hopper 12, having an entrance 12'. This hopper is carried on a shaft 13, which is continuously rotated in any suitable manner.

The hopper is conical in shape and its 80 larger end abuts against a plate 14, which forms a closure. The larger end of the hopper is provided with a plurality of recesses 15 adapted to admit individual plates. Projections 17 between the recesses 15 serve 85 to move the plates as the hopper rotates in the direction of the arrow of Fig. 4. The flange 16 supports the plates and guides them to the top of the guide 11. A spring 18 serves to yieldingly hold the plate, which 90 is just emerging from behind the base of the hopper at the top of the guide 11. When the guide 11 is filled up, plates which subsequently arrive at the top of the guide are deflected and allowed to fall out through 95 the overflow guide 19 into a suitable receptacle, from which they can be again placed in the hopper.

An annular flange 20 is provided at the base of the hopper, spaced apart from the 100 abutment 14 sufficiently to allow a single layer of plates to fall down between the flange 20 and the abutment 14. On account of the shape of the hopper and the arrange-

ment of this flange, the movement of the hopper keeps the plates tumbling over each other and falling toward the flange 20, and some of these plates fall over the flange 5 and down into the recesses 15, whence they are moved to the top of the guide 11.

At the bottom of the guide 11 is a movable support 21 hinged at 22 and drawn yieldingly upward by a spring 23 against 10 a stop 24 at or near the lower end of the guide 11. This support is grooved to fit the edge of one of the plates, as indicated at 25. A lateral support 26 assists in positioning the lower edge of the plate and the overhanging nose 27 assists in holding the upper edge of the plate.

The partially hooked links 30 are supplied on a guide 31, which is secured to a stationary member 32 by means of clamping bolts 33, which permit the lateral adjustment of the link guide relative to the plate guide.

The links on the guide 31 are supported by a yielding member 34 adapted to be 25 moved inward by a pair of cut-off knives 35, as indicated in my former application #874,595. When the knife 35 moves the support 34 inward, it releases the bottom link on the guide and allows it to fall on the feed plunger 36. In the next stroke of 30 the feed plunger 36, the link falls upon the flanges 37, which are immediately below the feed plunger and which support the link on the plane of the front edge of the plunger. The flanges 38 extend over the flanges 37, so as to allow the plunger 36 to operate beneath the guide 31, but so as to hold the ends of the link and prevent them from tilting. The links are further positioned by the 35 stationary members 31'. The feed plunger 36 and the cut-off knives 35 are carried by a slide 40 operated by a cam 41 on the shaft 42. The flanges 37 and 38 are carried by dies 39, 39'.

45 Dies 43 and 44, grooved on their forward faces, as indicated by the dotted lines in Fig. 2, co-act with the hooked ends of the links, as the links are fed forward by the plunger 36, to partially close or bend the 50 hooks.

The horizontal grooved dies 39, 39' are shaped at the ends to cause the ends 30', 30² of the link to be bent over as the ends pass through the apertures in the plates 10', 10². 55 The die 44 is carried by a holder 47, and is horizontally adjustable along the guides 45, 46 so as to bring it into its proper position for links of different lengths. The die 43 and the holder 47 are both carried by a slide 60 48 operated by the cam 49 on the shaft 50 and are adjustable toward and from the strand guide 45. The completion of the closing movement of the hooks is performed by dies 51, 51' on a holder 52 on the slide 65 48. The holder is adjustable toward and

from the strand guide and the dies 51, 51' are adjustable along the strand guide to accommodate links of different lengths. The body of the link is supported opposite dies 51, 51' by die 39 and a plate is held adjacent one die 51' by a fork 53' carried by slide 54 operated by cam 55 on the shaft 42. 70

An auxiliary strand support 56 is adjustable on the guide 45 for holding and guiding the strand adjacent the die 51, but this 75 may be omitted.

The strand is intermittently pulled along through the horizontal strand guide, for instance, by the mechanism shown in Bigelow Patent No. 1,043,898. The forked plunger 60 which engages the edges of the plates of the strand is carried by a slide 61, operated by an eccentric 62 on the shaft 63 with an eccentric strap 64 and the connecting rod 65, which is extensible like a turnbuckle 85 for adjusting the draw-out or strand feeding stroke so as to bring the plate 10² against the positioning fork 53'.

The shafts 42 and 63 are connected by miter gears 66. The shafts 50 and 63 are 90 connected by miter gears 67.

In the operation of the mechanism, the guide 11 is continuously kept filled with the perforated plates by the action of the hopper 12. The bottom plate 10' is supported 95 by the yielding member 21. The plate 10² is suitably supported in the strand guide and the hooked link fed forward so as to engage in apertures of the plates, as indicated in Fig. 5. The hooks 30' and 30² are bent 100 over by dies 39', 39, 43 and 44, as the link is fed forward by the plunger 36. As the strand is drawn along intermittently, the plate 10' is tilted up, so that its diagonal axes are vertical and horizontal, respectively. 105

This construction and arrangement permits of uniform and rapid action, even though the plates may be more or less irregular, as they often are in commercial practice.

What I claim is:—

1. In a machine of the character described, a feed hopper mounted to rotate on a substantially horizontal axis, said feed hopper 115 being open at one end and having plate feeding projections on said open end, a substantially vertical abutment at said open end of the hopper for confining the articles being fed in the pockets provided between 120 the plate feeding projections and an inwardly extending annular flange at the open end of the hopper spaced inwardly from the abutment a distance sufficient to enable a single row of the articles being engaged between 125 the same and the adjoining face of the abutment and said annular flange extending inwardly into the hopper sufficiently to substantially support the mass of articles within the hopper and thereby prevent said mass 130

from interfering with the feeding of the single row of articles confined between the flange and the abutment.

2. In a machine of the character described, 5 an open - ended hopper mounted to rotate on a substantially horizontal axis and provided with plate feeding projections at the open end thereof, an abutment forming in conjunction with said projections a feeding 10 passage for the plates, a plate guide having an entrance end adjoining said passage, and a spring for yieldingly guiding the plates in transit from said passage to the entrance of the plate guide.
- 15 3. In a machine of the character described, a vertical plate guide, means for automatically supplying plates on edge at the upper end of said guide, an overflow guide to dispose of an excess of plates at the upper end 20 of said plate guide, and means for periodically withdrawing plates from the bottom of said plate guide.

4. In a machine of the character described, a feed hopper having means at one 25 end thereof for feeding the blanks from within the hopper, a guide for such blanks having an entrance mouth disposed to receive blanks fed by the hopper, and an overflow guide having an entrance mouth 30 adjoining the entrance to the first guide and adapted to receive overflow blanks from the first guide.

5. In a machine of the character described, a feed hopper, a horizontal strand guide 35 beneath the feed hopper, a vertical plate guide extending in a direct line from said feed hopper to said strand guide, means for applying links to the plates at the strand guide, and means for drawing the stranded 40 links and plates through the strand guide.

6. In a machine of the character described, a vertical plate guide, a yielding plate support at the lower end thereof, a horizontal strand guide leading from said plate guide, 45 and means for inserting a link from the side to engage a plate held on said support.

7. In a machine of the character described, a strand guide, a yielding plate support at one end thereof, a stationary positioning 50 nose overstanding said support, and means for inserting a link in a plate held between said support and said nose.

8. In a machine of the character described, a plate guide, a hinged support at the bottom 55 thereof, means for positioning a perforated plate on said hinged support, means for inserting a hook of a link in a perforation of said plate, means for pulling said link and plate, and means for turning the 60 plate diagonally on edge.

9. In a machine of the character described, means for supporting two perforated plates spaced apart from each other, a link guide, a feed plunger, supports for the ends of a 65 link beneath said guide, flanges over said

supports to steady the ends of the link, and dies coöperating to bend the hooks of a link being fed between said supports and flanges.

10. In a machine of the character described, a strand guide, link feeding means 70 and link holding means arranged on one side of said guide, hook bending means opposite said feeding means, hook closing means opposite said holding means, and an adjustable auxiliary link guide mounted adjacent the operative positions of said holding and closing means.

11. In a machine of the character described, two shafts arranged on opposite sides of the machine and an end shaft connecting said side shafts, transversely operating link feeding means driven by one side shaft, transversely operating link bending means driven by the opposite side shaft, and longitudinally operating strand draw-out 85 means driven by the said end shaft.

12. In a machine of the character described, a substantially vertical plate guide, a yielding plate support at the lower end of said plate guide, a substantially horizontal strand guide extending laterally from the lower end of the plate guide, means for applying a connecting link to the plate on the yielding plate support and a plate within the strand guide, and means for passing 95 the stranded links and plates through the strand guide.

13. In a machine of the character described, a substantially vertical guide for a plurality of substantially rectangular perforated plates superposed edge to edge, a horizontal support for the lowermost plate of said plate guide, a laterally extending strand guide adjacent the lower end of the plate guide, means for supporting a plate in 100 diagonally disposed relation within the strand guide, means for inserting a connecting link in a perforation of said diagonally supported link within the strand guide and in a perforation in the horizontally supported 105 plate at the foot of the plate guide, means for passing the stranded links and plates through the strand guide, and means for turning the horizontally supported plate to a diagonal position as it passes into the 110 strand guide.

14. In a machine of the character described, the combination of a plate guide, a rotating hopper at the upper end thereof having a plurality of spaced thin pockets 120 opening into the interior of said hopper, each pocket being substantially the thickness of a plate for delivering the plates separately and on edge into said guide, and an overflow chute from the upper end of said guide.

15. In a machine of the character described, a strand guide, a laterally movable abutment movable into said guide and having oppositely inclined shoulders, a plate 125 guide, a yielding abutment at the lower end 130

of said plate guide having a horizontal plate-supporting shoulder, and means for feeding links into the perforations in plates supported respectively against said inclined 5 and horizontal shoulders.

16. In a machine of the character described, a strand guide, means for assembling hooked links and plates at one end of said guide, an abutment at one side of 10 said guide adjustable longitudinally thereof, link-closing dies movable laterally of said strand guide at the side opposite said abutment, and a plate-holding member movable into said guide above and below said abutment, one end of said abutment serving as 15 a support for one end of the links in the assembling operation.

17. In a machine of the character described, a horizontal strand guide, means 20 for assembling links and plates at one end thereof, dies for partially closing the hooked ends of the links at the assembling position, a stationary link abutment at one side of said strand guide, hook-closing dies on the 25 opposite side of said strand guide, and an adjustable stop for the plates of the strand extending above and below said abutment opposite one of said closing dies.

18. In a machine of the character described, a horizontal strand guide, means for 30 assembling links and plates at one end thereof, dies for partially closing the hooked ends of the links at the assembling position, a stationary link abutment at one side of said

strand guide, an adjustable stop for the 35 plates of the strand extending above and below said abutment opposite one of said closing dies, and a support for said stop adjustable longitudinally of said strand guide.

19. In a machine of the character described, a plate guide, a link guide, means for feeding a link into a plate at the bottom of 40 said plate guide, a strand guide, a stop movable laterally into said strand guide adjacent the edge of said link guide opposite the 45 plate guide, and a support for said stop permitting adjustment of said stop longitudinally of said strand guide, said stop having oppositely inclined shoulders serving as abutments for the upper and lower inclined 50 edges of a plate.

20. In a machine of the character described, a vertical plate guide, a movable abutment at the lower end thereof, a guide member extending partially across the outer 55 face of said plate guide above said abutment, a strand guide, a stop movable laterally into said strand guide and having oppositely inclined plate-engaging shoulders, and means for moving a link to insert one end 60 into a plate supported on said abutment and inserting the other end into the plate held against said stop.

CHARLES W. PECK.
